WHEEL COVER

George J. Pyshe, Southfield, Mich., assignor to General Motors Corporation, Detroit, Mich., a corporation of Delaware

Filed Aug. 31, 1964, Ser. No. 81,510

Term of patent 7 years

(Cl. D14—30)

I claim:

The ornamental design for a wheel cover, substantially as shown.
